HUGH D. YOAKUM, OF WACO, TEXAS, ASSIGNOR OF ONE-FOURTH TO J. KNOX GREER,
OF ALLEN, OKLAHOMA.

SWITCH MECHANISM.

1,130,459.

Specification of Letters Patent. Patented Mar. 2, 1915.

Application filed June 1, 1914. Serial No. 842,106.

To all whom it may concern:

Be it known that I, HUGH D. YOAKUM, residing at Waco, in the county of McLennan and State of Texas, have invented certain new and useful Improvements in Switch Mechanisms, of which the following is a specification.

This invention, which in its general nature relates to improvements in switch throwing mechanisms, is more particularly designed for use in street railway systems in which the switch is set by means of tripping devices carried by the car and under control of the motorman.

Primarily, my invention has for its purpose to provide a simple, inexpensive and easily operated mechanism of the general character stated, in which the actuating devices are such that the switch, when shifted, to either of its set positions is positively held to such position, tripping means being also included of peculiar design adapted for being engaged by the actuating member on the car and controlled by the motorman.

With other objects in view that will hereinafter appear my invention consists of the peculiar construction and novel arrangement of parts, all of which will be herein-after fully explained, specifically pointed out in the appended claims and illustrated in the accompanying drawings, in which:

Figure 1 is a plan view of my switch mechanism, the switch members being shown at their open or siding position. Fig. 2 is a transverse section thereof on the line 2—2 on Fig. 1. Fig. 3 is a plan view of the pawl and ratchet mechanism for actuating the shaft that carries the cam devices that coöperate with and control the shifting of the switch bar. Fig. 4 is a vertical section of the parts shown in Fig. 3 and taken substantially on the line 4—4 on Fig. 3. Fig. 5 is a detail section of the bell crank or actuating lever that controls the pawl and ratchet mechanism shown in Fig. 3. Fig. 6 is a vertical section, parts being in elevation of the adjustable tripper devices mounted on the car platform adapted for

engaging the actuating lever for the pawl and ratchet mechanism shown in detail in 50 Fig. 3, the raised position of the said tripper devices being indicated in dotted lines. Fig. 7 is a detail view of the double faced cam disk presently again referred to.

In carrying out my invention, I arrange 55 the switch members 1—1 for being positively shifted and held to the shifted position whenever the actuating lever is engaged by the tripping devices, the latter in my construction of switch mechanism being 60 arranged for being normally shifted up and out of an operative condition so that the car can readily move along over the switch devices without disturbing them.

2—2 designate the main track rails and 65 3—3 the siding rails.

At a point under the switch rails 1—1 and extended transversely thereof, is a housing or space in which is mounted a transversely disposed actuating shaft 4, hereinafter 70 termed the switch controlling shaft, since it is the rotary movement thereof that actuates the means that shifts the switch bar 5, presently again referred to. Shaft 4 is suitably mounted upon standards 6—6 and end 75 bearings 7—7 and at each side of its central point it carries a coiled spring 8, the inner ends of which engage the inner bearings or standards 6, while the outer ends engage collars 9 on the shaft (see Figs. 2 and 3). 80 The object of the springs 8 is to provide for equalizing the tendency of end thrusts on the shaft 4, which turns loosely on its bearings during the operation of shifting the switch bar as will hereinafter more fully 85 appear. Midway thereof the shaft 4 carries a cam disk 10 the opposite faces of which are each provided with a set of cams 11—11 and 12—12, the said cams 11—11 and 12—12 being disposed diametrically opposite each 90 other and the cams 11—11 at right angles to the set of cams 12, 12, to provide, as it were, four radially disposed and equally spaced cams, alternately arranged so that during the rotation of the disk, a cam at one 95 side operates to throw the switch bar in one

direction and on continued rotation of the said shaft, a cam on the other side will throw the said bar in the reverse direction.

As is best shown in Fig. 2, the switch bar 5 has a pair of pendent brackets 50—50 that straddle the cam disk 10, and each of which carries a horizontal bearing roller 51—51 for engaging with the wedge-like cams 11—12 on the opposite faces of the disk 10, as shown.

At one end the shaft 4 has a ratchet disk 40 provided with four ratchets or teeth spaced in harmony with the cams on the disk 10 and with the said ratchet disk 40 operates an oscillating pawl arm 15 that carries two dogs or members 16—16 that engage the ratchet disk 40, as is best shown in Fig. 4. To the pawl arm 15 is pivotally connected a pull rod or lever 17 that extends lengthwise of the trackway and pivotally joins with the lower end of a crank arm 18 fast on a rock shaft 19 mounted transversely of the said trackway and with which fixedly connects the actuating lever 20 that projects up above the trackway in position to engage with tripper devices on the car body, the said lever and the arm 18 forming, as it were, a bell crank lever for the rock shaft 19. The pawl arm 15 is loosely hung from the shaft 4 and it is swung back to its normal position by a retracting spring 30 and to avoid jarring the said arm on its returned movement, a buffer spring 21, mounted on a rod 22 attached to the arm 15, is provided that operates in the manner clearly understood by reference to the drawing.

By reason of the peculiar construction and novel arrangement of the several parts hereinbefore described and shown, assuming the switch members to be in the position shown in Fig. 1, and a car to be moving along in the direction of the arrow, which is to proceed along the main line, the tripper devices on the car platform are lowered by the motorman to engage the lever 20 and in doing so it pulls the rod 17 in the direction of the arrow (see Fig. 4) and turns the shaft 4 in the direction indicated, and causes the cam disk, which is now positioned as shown in Fig. 2, to move the switch bar to throw the switch members over to connect the main line rails, it being understood that the next time the lever 20 is pressed against, the same operation of the parts occurs, except that a cam on the other side of the disk engages the switch throw bar and moves it in the other direction to open the main line.

Any suitable tripping device may be used in the car platform for engaging the actuating lever 20, but I prefer to use the simple arrangement of parts shown in Fig. 6, which consists of a pivoted lever 22 having a spring latch for slipping into engagement with the rack guide 23 and whose lower end

carries a lateral stud 24 that slidably moves 65 on the longitudinal slot 25 in a pendent arm 26 pivotally hung from the underside of the platform 27 in the lower end of which is pivoted a tripper 28 for engaging the lever 20 whose upper end extends and engages a 70 buffer spring device 29 mounted on the arm 26, as is clearly shown in Fig. 6 of the drawing.

From the foregoing description taken in connection with the accompanying drawing, the complete construction, the manner in which my invention operates, and the advantages thereof will be readily understood.

In practice, the switch throwing arm may have an extension for coöperating with a 80 signal lantern, as shown in Figs. 1 and 2.

What I claim is:

1. In a switch mechanism of the character described, the combination with the switch members and the switch bar, said bar having 85 a pair of oppositely disposed pendent bearings, of an operating shaft, bearings in which the shaft is loosely mounted, a cam disk on the shaft having alternately disposed cams on its opposite faces for coacting 90 with oppositely disposed pendent bearings on the switch bar, means for cushioning and equalizing the end thrusts on the said operating shaft, means for imparting intermittent rotary movement in one direction, said means including a pawl and ratchet mechanism, a bell crank lever device operable by 95 a passing car, and connections that join the said bell crank lever and the pawl and ratchet devices.

2. In a switch mechanism of the character described, the combination with the switch members and the switch bar, said bar having a pair of oppositely disposed pendent bearings, of an operating shaft, bearings in which the shaft is loosely mounted, a cam disk on the shaft having alternately disposed cams on its opposite faces for coacting 105 with oppositely disposed pendent bearings on the switch bar, means for cushioning and equalizing the end thrusts on the said operating shaft, means for imparting intermittent rotary movement in one direction, said means including a pawl and ratchet mechanism, a bell crank lever device operable by a passing car, connections that join the said bell crank lever and the pawl and ratchet devices, and means for automatically 110 returning the pawl and ratchet devices to the normal position.

3. In a switch mechanism of the character described, the combination with a pair of oppositely disposed switch members and a switch bar that connects said members, the said bar including a pair of oppositely disposed pendent bearings; of an operating shaft, bearings in which the said shaft is loosely mounted, a disk mounted on the shaft 115

to turn therewith having oppositely disposed cam faces for co-acting with the oppositely disposed pendent bearings on the switch bar, means for equalizing the end thrusts of the 5 aforesaid operating shaft, other means for imparting intermittent rotary movement to the said shaft in one direction, and a bell

crank lever device operable by a passing car and co-operatively connected with the ratchet mechanism.

HUGH D. YOAKUM.
